CLAIM

The ornamental design for a cabinet, as shown and described.

DESCRIPTION

FIG. 1 is a perspective view of the cabinet.

FIG. 2 is a front elevational view of the cabinet; and,

FIG. 3 is a side elevational view of the cabinet with the opposite side being a mirror image of the same.

Portions of the design shown in broken lines form no part of the claimed design.

The bottom and back portions of the cabinet form no part of the claimed design.
